(57) **CLAIM**

The ornamental design for a needle protector support, as shown and described.

DESCRIPTION

FIG. 1 is an oblique view of needle protector support showing our new design;

FIG. 2 is a left side elevation view of thereof, the right side elevation view being a mirror;

FIG. 3 is a front elevation view thereof;

FIG. 4 is a top plan view thereof;

FIG. 5 is a rear elevation view thereof; and,

FIG. 6 is a bottom plan view thereof.

The dash dot lines immediately adjacent to the claimed area represent the boundaries of the claimed design. The dashed lines in the figures illustrate the portions of the design that form no part of the claimed design. None of the broken lines form any part of the claimed design.
